[57] CLAIM

The ornamental design for a pop open hamper, as shown and described.

DESCRIPTION

FIG. 1 is a perspective view of a pop open hamper incorporating our new design;

FIG. 2 is a top plan view thereof;

FIG. 3 is a front elevation view thereof;

FIG. 4 is a rear elevation view thereof;

FIG. 5 is a left side elevation view thereof with the right side elevation view being a mirror image of the left side elevation view;

FIG. 6 is a perspective view of the alternative embodiment;

FIG. 7 is a top plan view of the alternative embodiment;

FIG. 8 is a right side elevation view of the alternative embodiment;

FIG. 9 is a left side elevation view of the alternative embodiment; and,

FIG. 10 is a front elevation view of the alternative embodiment with the rear elevation view of the alternative embodiment being a mirror image of the front elevation view of the alternative embodiment.

The pattern which is partially shown for ease of illustration, represents a conventional fabric and is understood to repeat uniformly throughout the indicated area.
